CLAIM

The ornamental design for a storage panel, as shown and described.

DESCRIPTION

FIG. 1 is a front perspective view of a storage panel, showing our new design;

FIG. 2 is a front plan view thereof;

FIG. 3 is a rear plan view thereof, opposite that shown in FIG. 2;

FIG. 4 is a side view thereof;

FIG. 5 is a side view thereof, opposite that shown in FIG. 4;

FIG. 6 is an end view thereof;

FIG. 7 is an end view thereof, opposite that shown in FIG. 6;

FIG. 8 is a front perspective view thereof in a raised configuration;

FIG. 9 is a front plan view of the storage panel shown in FIG. 8;

FIG. 10 is a rear plan view thereof, opposite that shown in FIG. 9;

FIG. 11 is a side view of the storage panel shown in FIG. 8;

FIG. 12 is a side view thereof, opposite that shown in FIG. 11;

FIG. 13 is an end view of the storage panel shown in FIG. 8;

FIG. 14 is an end view thereof, opposite that shown in FIG. 13;

FIG. 15 is a front perspective view of the storage panel of FIG. 1 in an exemplary environment; and,

FIG. 16 is a front perspective view of the storage panel of FIG. 1 in another exemplary environment.

The broken lines shown herein are for illustrative purposes only and form no part of the claimed design.
